UNITED STATES PATENT OFFICE.

ALBERT H. DE VOE, OF WESTFIELD, NEW JERSEY, ASSIGNOR TO THE SINGER MANUFACTURING COMPANY, OF ELIZABETH, NEW JERSEY, A CORPORATION OF NEW JERSEY.

POWER TRANSMITTER.

Original application filed June 14, 1917, Serial No. 174,647. Divided and this application filed April 7, 1921. Serial No. 459,881.

To all whom it may concern:

Be it known that I, ALBERT H. De Voe, a citizen of the United States, residing at Westfield, in the county of Union and State 5 of New Jersey, have invented certain new and useful Improvements in Power Transmitters, of which the following is a specification, reference being had therein to the accompanying drawings.

10 This invention relates to power-transmitters for conveniently and positively controlling the operation of small machines such as sewing machines including the casing or housing for supporting and enclosing 15 the moving elements of such transmitters to prevent the clothes of operatives or the work being caught therein and also to protect said elements from dust and dirt, but at the same time to allow easy access to them to facilitate inspection and repair.

This application is a division of my co-pending application Serial No. 174,647, filed June 14, 1917.

The invention also consists in certain details of construction which will appear from a detailed description thereof in connection with the accompanying drawings, in which Fig. 1 is a side elevation of a power-bench, showing two machines and transmitters therefor in working relation. Fig. 2 is a longitudinal section of the transmitter casting in a vertical plane through its axis, most of the movable parts enclosed therein being shown in elevation. Fig. 3 is a section at 35 right angles to the axis of the shaft on substantially the line 3—3 of Fig. 2 and looking in the direction of the arrows. Fig. 4 is a rear side elevation of the transmitter casting. Fig. 5 is a cross section showing in detail a latch which renders a section of the housing or casing conveniently detachable. Fig. 6 is a detail of a preferred form of universal joint for connecting the shaft sections.

As shown in the drawings, on the power-bench 1, sewing machines 2 having belt-wheels 3 are supported at intervals allowing operatives sufficient freedom from interference with one another. Below the bench transmitters are secured preferably adjacent the bench-legs 4 which are bolted to cross-bars 5 suitably secured to batten-plates 6 fastened to the bench adjacent the ends of abutting table units of the bench as shown and described in my patent for power tables, No. 1,320,455, dated October 28, 1919.

The vital parts of the transmitter are enclosed within a housing or casing consisting of a cap-plate 7, a main section 8 and a removable section 9. The cap-plate 7 is provided at each end with an apertured lip 10 receiving the screws 11 for securing it to the table. All the component parts of the transmitter are carried by this plate. The main section 8 is adjustably secured at opposite ends of the cap-plate 7 by means of two 65 centrally arranged tension bolts 12 fitted to slots 13 in the main section and pairs of thrust screws 14 are tapped into the main section on both sides of the bolts 12 with their ends resting against the cap-plate 7. 70 The removable section 9 is formed with a lip or offset 9' extending under the main section 8 to close the bottom thereof, and also to provide a cup-portion to catch excess oil. It is detachably secured to section 8 by 75 a latch 15, see Figs. 2 and 5, pivoted at 16 to a bearing section 18 secured to the main section 8. The latch 15 is U-shaped and its under leg 15' is adapted to engage a groove 17' in a wing 17 of the removable section. 80 From this groove the latch may be readily disengaged by an extension 15'' thereof within convenient reach of the operative at the front of the bench. The beforementioned bearing section 18 is secured to the 85 main section 8 by clamp-screws 19 and is formed with a boss 20 which is adapted to receive the set-screw 21 for securing a bearing or bushing 22 in place.

On the bearing sleeve 22 the hub 23 of a 90 driven clutch-member 24 is freely rotatable, the friction of the end thrust of driving relation being provided against by the ball bearings 25. To the driven clutch-member 24 a belt-wheel 24' is fastened as described in the 95 parent application. A belt 3' leads from this wheel to the pulley 3 on the machines to be driven.

In the bearing sleeve 22 is supported one end of an individual transmitter shaft section 26, the other end of which turns freely in a bearing 27 integral with the main housing section 8, see Fig. 2. The shaft section 26 is connected at opposite ends to the shaft 28 joining the two transmitters by means 105 of universal couplings 29 which permit transmission of the power through shaft sections whose axes are out of parallelism and intersect at an obtuse angle. The driving member 30 is mounted to turn with the 110

shaft 26 but is slidable thereon so that it may be engaged with and disengaged from the driven member 24 by means of the rocking arm 31 connected with member 30 and having anti-friction rollers 32 cooperating with the resilient cam-members 33 all as fully disclosed in my parent application above mentioned. This rocking arm is operated from a treadle 34 by means of the adjustable connection 35.

Ample lubrication for those portions of the shaft which are subjected to wear is afforded by the wire-rings and wells shown at 36 and 37 in the bearings 20 and 27 respectively.

Surrounding the universal joint at opposite ends of the transmitter are truncated housings 38 and 39 between which a tubular casing 40 for the shaft section 28 is supported and held against endwise movement by the screws 41.

From the foregoing description it will be clear that the vital parts of the transmitter are accessible for repair or adjustment by reason of the removable section 9 of the housing and also by reason of the external location of the inclined cam-arms 33. At the same time the running parts are all enclosed so as to be protected from dirt and to fully protect the operative from injury.

Furthermore it will be apparent that the universal joints between the shaft sections eliminate the binding and friction losses inevitably concomitant to the use of a continuous line shaft for driving a plurality of machines. Further the operation of lining up the plurality of transmitters with the construction disclosed requires far less precision than it would with a continuous line of shafting enabling it to be done by low grade mechanics.

Having thus set forth the nature of the invention, what I claim herein is—

1. In a casing for housing and supporting power-transmitters, a power-shaft, a supporting cap-section, a main housing section, a bearing for said shaft secured to said main section and a removable housing section detachably secured to said main section and having an offset lip or cup-portion defining the bottom portion of the casing for catching excess oil.

2. In a power-table, a unitary power-transmitter having a shaft, a combined housing and hanger for said transmitter and

shaft having relatively detachable sections, tension members arranged to permit bodily lateral adjustment of the shaft substantially in parallelism with the table, and thrust-members arranged to permit both bodily lateral adjustment of the shaft at right angles to said table and tilting of the shaft into parallelism with the table.

3. In a power-bench, a plurality of transmitters having driving and driven members, a housing for said members of the transmitters, transmitter shaft-sections, coupling shaft-sections between said transmitter shaft-sections, universal joints connecting the several shaft-sections, and a tubular housing for said coupling shaft-section detachably supported by said first-mentioned housing whereby all the rotating parts are enclosed to protect the operative.

4. In a power-table, a plurality of power-transmitters adapted to be driven from a centrally arranged power-shaft, including individual shaft-sections for each transmitter and intermediate coupling shaft sections, and universal joints connecting the individual and intermediate shaft-sections whereby friction losses from inaccuracies in alinement of the transmitters may be diminished.

5. In a casing for housing and supporting power-transmitters, a power-shaft, a main housing section open at the side and lower portion thereof, a section secured to one side of said main housing section and having a bearing for said shaft, a removable housing section secured to said bearing section and closing the open side of the main housing section, said removable housing section having a lower portion closing the open lower portion of the main section, and means for detachably securing said removable section to said bearing section.

6. In a casing for housing and supporting power-transmitters, a main housing section open at one side and the bottom thereof, a shaft, a removable section secured to the main housing section to partially close the side thereof and provided with a bearing for the shaft, and a second removable housing section adapted to close the bottom of said main section.

In testimony whereof, I have signed my name to this specification.

ALBERT H. DE VOE.
